PILLOW OR THE LIKE

Marie Bentivoglio, New York, N. Y.

Application January 22, 1937, Serial No. 121,764
Renewed December 14, 1938

4 Claims. (Cl. 5—338)

This invention relates to a physiological pillow or the like and refers particularly to the type having a pair of raised wing portions spaced apart by an intermediate lower and generally flat portion which rises at an inclination toward the rear and at the front edge is bounded by a small roll of stuffed material.

The main object of my invention is to provide a pillow of the general character indicated which is primarily made to fit the upper portion of the body of the user and will properly support the neck as well as the head and which will, in addition relieve all neck and shoulder strains and will allow a good chin and throat line to result and also leave the shoulders clear.

Another object is to have such a pillow which is decidedly pleasing and attractive in appearance and which directly contributes to the beauty, comfort and health of the user.

A further object is to produce a pillow of this type which has a clearance for the head-dress of the user in order to avoid disturbing the hair, and supports the cheeks and sides of the head in such manner as to prevent formation of crush wrinkles on the face, while reducing noise by obstructing access of the same to the ears.

Still other objects are to make the pillow so that it will fit various sizes of heads and allow ventilation of the top of the head without drafts and free access of fresh air to the face, and will also allow a bed to be dressed or made up as usual, while being withal so practical and easy to manufacture as to recommend itself to the majority of people as a very desirable article.

Other objects and the various advantages accruing from the principles, form and nature of my invention, will appear more fully as this specification proceeds.

In the accompanying drawing forming part hereof,

Fig. 1 is a plan view drawn slightly in perspective and illustrating a pillow embodying the invention in a practical form which exhibits the salient features and principles thereof.

Fig. 2 is a front elevation of the same.

Fig. 3 is a section on line 3, 3 of Fig. 2.

Throughout the views, the same reference numerals indicate the same parts.

It is often the experience of people upon getting up in the morning, of finding that the neck is uneasy and that the muscles of both neck and shoulders may actually ache from strain caused by insufficient neck support during sleep, and also that perhaps a double chin and facial crush wrinkles have begun to appear, not to mention

that the hair is so sadly messed that the same requires to be completely gone over and remade into a proper head dress. This is especially true of women who are at all particular about their personal appearance, while on the other hand, the matter of convenience, comfort and proper rest is always important to everyone lying abed.

Bearing these points in mind, and particularly with the foregoing objects in view, the invention has been designed to provide a pleasant solution to several problems.

Hence, in the practice of my invention, a pillow, generally indicated at 1, is made with a pair of similar but opposite pillow wings in the form of more or less stuffed cushion portions which are spaced apart by a generally flat, forwardly inclined lower head rest portion 4, which terminates rearwardly at the edge 16. The pillow wing or portion 2 has a curved inner edge 5 of preferably varying height which forms the boundary along one side of the head rest portion, while the other portion 3 has a similar opposite inner edge 6 bounding the other side of the head rest portion. The curved edges 5 and 6 of the pillow wing portions are continued forwardly beyond the head rest portion in the form of the forward curved edges 18 and 19, respectively.

The rear edges 9 and 10 of the pillow portions 2 and 3, while connecting with edge 16 to form the rear edge of the pillow as a whole, may be sloped slightly forward as said edges approach the exterior sides 11 and 12 which form the ends of the pillow. These pillow ends may also converge slightly toward the rear so as to accentuate the pleasing effect of the curved portions of the pillow. However, the rear portion of the pillow, which is made up of rear edge portions 9, 10 and 16, is practically sheer and abrupt in form as shown at 16 in Fig. 3.

The front or near edge 17 of the central portion of the pillow is preferably curved inward, while at this edge, a roll or miniature bolster 7 forms the threshold or forward boundary of the head rest portion, and is designed to give direct support to the neck of a person when the head is laid back upon the head rest. The rear space 8 between the raised portions 2 and 3 will allow ventilation of the head while the sides 5 and 6 will steady the head and allow the same to be laid in a position along the length of said head rest wherein the sides of the face are gently and softly engaged against said sides 5 and 6 without wedging or any tendency to discomfort.

Thus, when the head of the user indicated at 55

- 20 is in comfortable position between the side portions of the pillow, the neck indicated at 22 will rest upon the front supporting roll 7, while the shoulders indicated at 23 and 24 will 5 nicely clear the curved forward edges 18 and 19 of said side portions. The result is that the head is allowed to recline rearwardly without bending the neck forwardly, the neck supported so as to remove muscular strain and consequent 10 fatigue, and the head dress allowed sufficient clearance rearwardly of the pillow, while the front part of the face is similarly afforded clearance to allow the head dress and entire face to maintain an undisturbed and desirable freshness 15 and smoothness in appearance. The purpose of this type of neck support and head rest is to provide a position of good poise of the head on the shoulders, in other words, substantially the same position and poise assumed by a person in a good 20 standing position.
- 20 The underside or bottom 25 of the pillow is preferably flat or convex as in the case of an ordinary bed pillow so that when the same is turned bottom up, the bed may be dressed as usual, leaving a central space which may be used 25 for pajamas or night dresses. The pillow as a whole is stuffed at 26 with down, feathers or any other filling material desired, and, of course, the differences between the height and form of the 30 head rest portion 4, the side wings or portions 2 and 3 and the front roll 7 are in a measure due to differences in the amount of stuffing each contains. The side edges of the head rest may be stitched down to hold the latter down to the 35 intended form and thickness, while being also stitched down at various points and also immediately behind the roll 7 to render the head rest quite compact and provide for the shape of said roll after being properly filled.
- 40 The two side wings and the head rest between may be separately filled, if preferred, but in any event, said side wings are intended to be softer and more yielding than the head rest.
- The curved sides 5, 18 and 6, 19, as well as the 45 head rest portion 4, the roll 7, side portions 2 and 3 and the underside 25, may all be made of a varying number of separate pieces of fabric according to the convenience or judgment of the manufacturer and these pieces properly stitched 50 to form the various outlines of the parts, these details being readily accomplished by any person skilled in handling fabrics and textiles generally.
- In order to increase the utility of the cushion 55 in logical manner, I also propose to have a pocket indicated at 15 in the wing portion 3 opening at the side 12 and preferably closed by a length of hookless fastener 13 controlled by the finger piece 14. A similar pocket may also be provided in the other wing 2 at 21 if found necessary, but details of the latter are omitted for clarity in the drawing. Obviously, when a person has a watch, 60 jewelry or even a sum of money at hand when retiring, it will be convenient and reasonably safe to place the mentioned valuable objects in the

pocket of the present pillow, drawing the finger piece 14 forward to close the same, and it will be easy to find again the same objects in known location upon rising.

Other means than the type of fastener mentioned may be used for closing the pocket or pouch 15, for example, a draw cord passed through loops on the edges of the pocket, or buttons and corresponding button holes, etc., may be used, these means being well known expedients 10 familiar to anyone skilled in the art.

If so desired, the opening of the pocket may be located on the upper portion of the wing 3, a few inches within the end 12, for the pocket would still be accessible from said end.

15 On the other hand, the present pillow will, of course, be provided with a slip, in the usual manner, but this slip may, with equal effectiveness, contain the pocket instead of the pillow.

20 From the foregoing description, it is apparent that the head does not lie on the wings although these may function as normal pillows. These wings may therefore be decorated in a variety of ways and somewhat modified upon the surfaces and external edges thereof to give pleasing optical 25 effects.

Manifestly, variations may be resorted to, and certain features used without others.

Having now fully described my invention, I claim:

1. A pillow or the like, comprising the combination of a substantially continuous underside forming a substantially flat foundation coextensive with the entire pillow, upon the upper side a pair of raised pillow wing portions spaced 35 apart and forming the two ends of the pillow, inner opposite edges upon said wing portions converging toward the rear edge of the pillow in order to accommodate heads of different breadth, the spaced relation of the wing portions providing 40 between them a generally flat depressed intermediate portion between said two wing portions terminating at the rear edge of the pillow, and a raised roll bounding said depressed portion at the front edge of the same, said pillow being stuffed 45 throughout its entire extent.

2. A pillow according to claim 1, wherein the raised roll at the intermediate portion of the front edge of said pillow is intermediately curved inwardly toward the rear edge of said pillow to narrow the section of the pillow through the 50 center.

3. A pillow according to claim 1, wherein the curved inner opposite edges of the pillow wing portions are continued forwardly in divergent 55 curved manner toward the front outer corners of said pillow.

4. A pillow according to claim 1, wherein the generally flat depressed intermediate portion is inclined upwardly toward the rear of the pillow from a lowest point behind the raised roll at the 60 front edge.

MARIE BENTIVOGLIO.
